(57) **CLAIM**

The ornamental design for a packaging container having surface ornamentation, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective view of first embodiment of the packaging container having surface ornamentation in a closed position showing our new design;

FIG. 2 is a front view thereof;

FIG. 3 is a rear view thereof;

FIG. 4 is a top view thereof;

FIG. 5 is a bottom view thereof;

FIG. 6 is a right side view thereof, the left side view thereof being a mirror image thereof;

FIG. 7 is a perspective view of a second embodiment of the packaging container having surface ornamentation in a closed position;

FIG. 8 is a front view thereof;

FIG. 9 is a rear view of the first embodiment packaging container having surface ornamentation shown in an open position; and,

FIG. 10 is a rear view of the second embodiment of the packaging container having surface ornamentation shown in an open position.

The surface ornamentation can be in one or more colors, but not a particular color or colors. Broken lines are included herein for illustrative purposes only and form no part of the claimed design.
